FRED STOGSDILL, OF CIMARRON, KANSAS.

CONVEYER AND STACKER.

1,237,573.

Specification of Letters Patent. Patented Aug. 21, 1917.

Application filed December 4, 1916. Serial No. 135,031.

To all whom it may concern:

Be it known that I, FRED STOGSDILL, a citizen of the United States, and residing in Cimarron, in the county of Gray and State 5 of Kansas, have invented a new and useful Conveyer and Stacker, of which the following is a specification.

My invention relates to conveyers and stackers, of the class which are used in lifting, conveying and depositing hay, straw, 10 fodder and other farm products from the field, in stacks, barns and other storage places.

The objects of my invention are—

First, to provide a durable, efficient and convenient conveyer and stacker which may be easily and cheaply constructed and transported from place to place about the field;

Second, to provide the platform which 20 revolves with a hollow mast having pivoted, adjustable, oppositely disposed booms with rigging adapted to turn the booms on their pivots.

Third, to provide within the mast a tube 25 which shall be rigid with the vehicle, and extend above and beyond the upper end of the mast, and having a bar with a cap movable in the upper portion of the tube, the cap carrying a plurality of pulleys to receive and direct cables employed in operating the 30 booms; and fourth, to provide the platform which revolves, with a pinion adapted to engage the rack mounted on the vehicle and impart motion to the revolving platform.

I attain these and other objects by means 35 of the mechanism and combination of parts illustrated in the accompanying drawing in which—

Figure 1, is a side elevation of the conveyer and stacker, partly sectioned to show 40 the method of mounting the operable parts on the vehicle;

Fig. 2, is a plan view from the top of the hub, and showing the integral arms which 45 support the rack;

Fig. 3, is a sectional view through the operable parts of the device on the line X—X, in Fig. 1, the booms and rigging being omitted;

Fig. 4, is a top plan view of the boom 50 and the ring with pivots, upon which pivots the booms turn;

Fig. 5, is a bottom plan view of the cap on the top of the mast and which provides 55 a bearing for the inner tube;

Fig. 6, is a bottom plan view of the cap on

the top of the inner tube and the pulleys carried thereby, and showing the bar integral with the cap in cross section, and

Fig. 7, is a top plan view of the revolute 60 platform, and showing the stationary platform surrounding the same.

Similar numerals of reference refer to corresponding parts throughout the several views.

Referring to the drawings—the wheels 1, axles 2, beams 3, cross-ties 4, and the pole 5, constitute the vehicle which is provided to support and transport the organized mechanism which will be hereinafter fully explained. A hollow hub 6, is provided circumferentially adjacent its lower end with a plurality of upwardly and outwardly extending integral arms 7, having equal radius, the ends of the arms are flattened to form a seat 8, adapted to lodge on the upper side of the beams and cross-ties and to receive a piece of mechanism, hereafter described. The upper end portion of the hub is broadened and the top end of the hub is machined 80 to provide a substantially flat surface to form a slide bearing 9. An annular rack 10, is provided with cogs 11, and lodged on the upper side of the seats 8 and fixed thereto by bolts 12, which pierce the rack and seats 85 and penetrate the beams and cross-ties.

A circular platform 13, is provided on its upper side with a centrally disposed boss 14, having a hollow core 15, adapted to register with the hollow core of the hub. An annular channel 16, is formed in the boss, the lower side of the platform beneath the boss is surfaced and adapted to bear on the slide bearing 9. A tube 17, is inserted in the hollow cores of the boss on the platform and the hub, so that the lower end of the tube shall lie substantially in the plane of the lower end of the hub. A bar 18, is inserted upwardly in the tube 17, for the purpose of adding strength and rigidity to the tube 100 and the parts assembled therewith. A pin 19, is extended through the lower ends of the hub 6, tube 17 and bar 18, to hold the parts mentioned in place.

A tube 20, is positioned over the tube 17, and its lower end is entered in the channel 16 in the boss 14, which provision assures the turning of the tube 20, with the turning movements of the platform 13, the tube 17, remaining stationary and immovable. A 110 cap 21, having an opening therethrough to form a bearing for the tube 17, is mounted,

on the top end of the tube 20. A cap 23, having oppositely disposed lugs 24, supporting pulleys 25, and a downwardly extending bar 26, fixed to its inner side and projecting into the tube 17, is movably lodged on the top of said tube.

A ring 27, adapted to fit on the tube 20, is provided with oppositely disposed horizontal pivot pins 28, and with oppositely disposed lugs 29, carrying pulleys 30, is 10 slidably mounted on the tube 20, and for the purpose of detaining the ring at any place on the tube, set screws 31, are extended inwardly through the ring, so that the 15 points of the screws may have opportunity to impinge on the tube to hold the ring in place. Booms 32, are preferably made of strips 33, assembled in pairs, the one of which is positioned so as to overlap the 20 other of the pair, thereby providing for the lengthening or shortening of the boom.

The overlapping and overlapped strips are held in place by a clamping device 34, which, when loosened, permits the sliding 25 adjustment of the boom. The assembled strips in pairs, as described, are beveled at their outer ends and secured together by fastening devices 35, and an eye 36 is attached to the joined ends of the strips. A pulley 37, is mounted between the strips a 30 little distance inwardly of the said end. A pivot bearing is apertured in the free ends of the side members of the booms and adapted to receive the pivots 28. A cotter-pin 38, is extended through the end portions of the respective pivot pins 28, outwardly of the booms, for the purpose of holding the booms on the pivot pins. A set 35 screw 39, is extended through the wall of the tube 17, and is adapted to impinge upon the bar 26, so that if the bar is raised to increase the height of the mast, the set screw shall operate to hold the bar aloft. The bar 40 26, normally is housed in the tube 17, and is turned in the turning of the booms. A narrow circular platform 40, surrounding the revoluble platform 13, is attached to the brackets 41, and forms a rigid and immovable walk about the revoluble platform for 45 the operator. A windlass 42 is mounted on the revoluble platform 13, at opposite sides of the tube 20, directly below the booms and each windlass is provided with a suitable cable 43, which is passed over the pulley 50 30, on the ring 27, and over the pulley 37, on the booms, and over the pulley 44, on the hinged forks 45, the end of the cables being fastened to the eye 36, at the end of the booms. This rigging provides means for 55 lowering and raising the forks. While I show manually operable windlass, it is understood that the windlass may be operated by any mechanical motive power, without departing from my invention. A crank 46, 60 having a shaft 47, connected therewith and

piercing the revoluble platform, and having a pinion 48, secured thereon below the platform, in engagement with the rack 10, provides means for revolving the platform and the apparatus connected therewith.

A cable 49, is attached to each eye 50, on the booms and is passed over one of the pulleys 25, on the cap 23, to the cleats 51, with which they are fastened. This provision is for lowering and raising the booms. A cable 52, is fastened to the upper end of the hinged fork 45, and passed over the pulley 25, and through the eye 53, and is dropped along the tube 20. A weight 54, is attached to the end of the cable to tension the cable. 70 This provision is for tripping the fork 45, to discharge its load.

The conveyer and stacker, when fully organized in the manner described, is conveyed to the material to be stacked or stored. The windlass operating the cable connected with the fork selected to lift the material, is turned backward, thus permitting the fork to drop to earth, where the fork is opened and closed upon the material to obtain a 85 load. The windlass is then turned forward, and the cable is re-wound and the fork is lifted to adjacent the outer portion of the boom. The pinion 48 is then revolved in 90 engagement with the rack 10, and the platform and all parts connected therewith, are revolved. The tube 20, being secured on the platform 13, is revolved, and it in turn revolves the booms 35, thereby the loaded fork is carried to the point or place selected for 95 stacking the material, within the reach of the booms. When the loaded fork arrives directly over the stack, the platform 13, is stopped, and the tripping cable 52, is pulled, and thereby the fork is opened and the load 100 drops by gravity upon the stack. At the time of the unloading of the fork, the fork on the opposite boom has been carried to the material and received its load, in the manner described in the case of the first 105 mentioned fork, and the platform 13, is again revolved to carry the loaded fork to the stack and the empty fork to the material. This procedure is repeated until the 110 work in hand has been accomplished. When the booms are swinging, the pressure of the cables against the pulleys on the cap 23, forces the cap and bar 26, connected therewith to turn in the same direction, thereby 115 the rigging will always bear substantially 120 the same relation to the operable parts of the apparatus.

If it is desired to extend the height of the mast, the bar 26, is raised a distance and held in place thereafter by the set-screw 39. 125 The forks 45, are assembled in the manner of tongues, and provided with a plurality of tines or prongs adapted to pick up and gather hay, straw and similar and other farm products, the tines or prongs not being 130

shown, a single tine is shown to illustrate the character of the forks.

Having described my invention and explained its mode of operation, what I claim is—

In a conveyer and stacker, the combination of a turntable, a vertically extending hollow mast mounted at the axis of said turntable, a collar slidably and adjustably mounted on said mast and provided with horizontally extending oppositely disposed pivot arms, oppositely disposed booms pivotally mounted on said pivot arms, said booms having extensible side members having their inner ends straddling said mast

and their outer ends converging to a junction, forks suspended by said booms, a tube piercing said turntable and extending upwardly through and above said mast and provided at its upper end with a rotatably mounted cap having a rigid leg depending within the tube, and means connected between said mast and said booms and supportingly engaged by said cap and adapted for rocking the booms on said pivot arms. 25

FRED STOGSDILL.
